CLAIM

The ornamental design for a pull-apart sheath introducer for percutaneous catheter introduction, as shown and described.

DESCRIPTION

FIG. 1 is a front perspective view of a pull-apart sheath introducer for percutaneous catheter introduction, showing my new design;

FIG. 2 is an enlarged front elevational view thereof, the rear elevational view being identical thereto;

FIG. 3 is a side elevational view thereof, the opposite side being identical thereto;

FIG. 4 is a top plan view thereof; and

FIG. 5 is a bottom plan view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 318,734

DATED : July 30, 1991

INVENTOR(S) : Mark H. Wyzgala

It is certified that error appears in the above-identified patent and that said Letters Patent is hereby corrected as shown below:

On the title page;

In the Attorney, Agent or Firm listing, "Anthony J. Beck" should be "Andrew J. Beck".

Signed and Sealed this

Twenty-second Day of December, 1992

Attest:

DOUGLAS B. COMER

Attesting Officer

Acting Commissioner of Patents and Trademarks
